REAR LUGGAGE COMPARTMENT LOCK

Ralph H. Wise, Detroit, Mich., assignor to
Ternstedt Manufacturing Company, Detroit,
Mich., a corporation of Michigan

Application November 20, 1940, Serial No. 366,365

3 Claims. (Cl. 292—110)

This invention relates to rear luggage compartment locks for automobiles. It is desirable to have a lock which will tension the parts and draw the lid tightly down upon the frame or jamb of the compartment opening to give a weather-tight seal with the weatherstrip and also to make the body rattle-proof. Locks with hook-like latches that are caused to draw into engagement with the keeper have been proposed and used. These accomplish the objective above referred to but they have been objectionable for the reason that they protrude from the lid when it is raised and many people have received bumps and injuries by not observing the protruding latch when they bend over to reach into the compartment.

It is the object of the present invention to provide a lock which will draw the lid tightly shut and which, at the same time when the lock is released, will draw up out of the way and retreat beyond the edge of the lid. This lock operates positively by means of pin and cam slots to be disengaged from the keeper member and to be withdrawn out of the way. This is important, if there is any luggage in the way when it is sought to open the lid. The bolt is definitely maintained in unlocked position out of the way by the relationship of the slots to the pins. The lock described and claimed in the following specification is the lock which will reliably achieve the objectives heretofore stated.

Referring to the drawings:

Fig. 1 is a longitudinal section through the lock showing the lid lock closed, taken on the line 1—1 of Fig. 2.

Fig. 2 is an elevation of the lock.

Fig. 3 is a section on the line 3—3 of Fig. 4.

Fig. 4 is a longitudinal section on the section line 4—4 of Fig. 3 and similar to Fig. 1 but showing the lock released and the locking arm withdrawn.

Fig. 5 is a plan view of a modified form in which two of these locks are used on a lid with the common actuating member on the up and down centerline of the lid.

Fig. 6 is an elevation of the modified form.

Referring to Fig. 1: 1 designates the rear compartment lid, 2 the body adjacent the rear compartment opening, 3 the jamb of the rear compartment opening, 4 a weatherstrip of soft, easily deformable rubber, such as sponge rubber, 5 the overlap flange of the lid and 6 the keeper or stationary hook that is bolted to the inside of the compartment by the bolt 7.

The locking parts are actuated by a handle on shaft 8 which is operated by a handle 9. On the end of this handle is a crank 10 connected by link 11 with slide 12. This slide is provided with flanges 13 to aid in guiding the slide in the casing 14 of the lock. Turned over ears 15 hold the

slide in place. The flanges 13 of the slide are provided with longitudinal slots 16 in which engages a pin 17 which is provided with a head at each end to hold the parts assembled. This pin is fixed to the locking arm 18. A second pin 19 passes through the flanges 13 and is fixed to the lock casing and is held in place by the distortion of the ends of the pin by punching, as at 20. This pin 19 passes through cam slots 21 in the sides of the locking arm. The locking arm has a hooked end or bill 22 adapted to engage in the gullet of the hook-like keeper 6 (as shown in Fig. 1).

The operation of the parts is as follows: Shaft 8 is rotated by handle 9. This causes the parts to move from the position shown in Fig. 1 to that shown in Fig. 4, passing through the three dotted line positions shown in Fig. 4 to the final position shown in full lines in Fig. 4. The bill of the locking arm takes the path shown by the arrow line A in Fig. 4, while the lid moves in the direction shown by the arrow B in Fig. 4. This movement of the locking arm is accomplished by the action of the two pins 17 and 19 in slots 16 and 21 respectively and the movement of the slide 12 by means of crank arm 10 and link 11. Slide 12 moves downwardly from the position shown in Fig. 1. The end of slot 16 picks up pin 17 fixed to the locking arm 18. This pushes the locking arm down from the position shown in Fig. 1 to the position X shown in dotted lines in Fig. 4. Inasmuch as the lower end of the cam slot 21 is straight and is nearly parallel to the slot 16, the movement of the bill of the arm is largely a straight line movement. There is a slight angular component, as shown by the arrow, due to the fact that a lower portion of slot 21 is at a slight angle to slot 16. As the curved portion of slot 21 reaches the pin 19, as shown in the dotted line Y showing of the hooked arm of Fig. 4, the locking arm begins to take an angular swing (as shown in Fig. 4). As the slide continues to push on pin 17, the locking arm swings around pin 19 as a pivot, the free end taking the arc-like course designated A in Fig. 4. At the same time, the pivot point of the arm changes a small amount due to the pin 19 moving along the curved portion of the cam slot 21 towards the right hand end which is shown achieved in the full line showing of Fig. 4. In this position, the locking arm is completely raised. It has passed through a swing of almost 180° and has been thrown up parallel with the wall of the lid and completely beyond the edge of the lid. In fact, it is swung up close to the lid so as to provide very little projection even on the inside of the lid. This makes the locking member very unlikely to come in contact with the head of one reaching into the compartment.

The locking of the member is just the reverse

movement and it is to be noted that, in the final movement of the handle, the locking arm and the bill are pulled up in substantially a straight line pull into a tight clamping engagement between the two hooks so as to firmly pull the overlap flange down against the deformable rubber weatherstrip 4 and make a weather-tight seal and a rattle-proof joint.

The locks contemplated in Figs. 5 and 6 are the same. The only difference is that the actuating handle 9 is put on the up and down centerline of the lid and the locks are put near the side edges of the lids so as to provide a better clamping and locking action than is had by a single lock at the center. The remote operating handle is connected with the cranks 23 on the ends of the operating shafts 24 of the locks. These connections are the long links 25 which are connected with the crank 26 that is attached to the handle operating shaft. Otherwise, the lock parts are the same.

What I claim is:

1. In a lock for a rear luggage compartment lid or other receptacle lid, the combination of a lock casing and a member guided in movement in said casing, a swinging locking arm with a hook-like end arranged to engage a keeper when in lowered depending position and connections between the guided member, the casing and the locking arm for giving the free end of the locking arm a swinging arc-like movement through a relatively long path of approximately 180° measured angularly for drawing the hook-like member into tight engagement with the keeper and releasing the same from engagement with the keeper and swinging it up under the lid and substantially parallel therewith.

2. In a lock for a rear luggage compartment lid or other receptacle lid, the combination of a lock casing and a member guided in movement in said casing, a swinging locking arm with a hook-like end arranged to engage a keeper and cam slot and pin connections between the guided member, the casing and the locking arm for giving the free end of the locking arm a swinging arc-like movement through a substantially 180° angular movement for drawing the hook-like member into tight engagement with the keeper and releasing the same from engagement with the keeper and swinging it up under the lid out of the way.

3. In a lock for a rear luggage compartment lid or other receptacle lid, the combination of a lock casing and a member guided in movement in said casing, a swinging locking arm with a hook-like end arranged to engage a keeper and cam and pin connections between the guided member, the casing and the locking arm for giving the free end of the locking arm a swinging arc-like movement through nearly a straight angle for drawing the hook-like member through a final substantially straight line movement to tightly draw the locking arm into engagement with the keeper and then releasing the same from engagement with the keeper and swinging it up under and substantially parallel with the lid out of the way.

4. In a lock for a rear luggage compartment lid or other receptacle lid, the combination of a lock casing and a member guided in movement in said casing, a swinging locking arm with a hook-like end arranged to engage a keeper and pin and slot guide and cam connections between

the guided member, the casing and the locking arm for giving the free end of the locking arm a swinging arc-like movement through a relatively long path measured angularly for drawing the hook-like member into tight engagement with the keeper and releasing the same from engagement with the keeper and swinging it up under and parallel with the lid out of the way.

5. In a lock for a rear luggage compartment lid or other receptacle lid, the combination of a lock casing and a member guided in movement in said casing, a swinging locking arm with a hook-like end arranged to engage a keeper and a straight guide slot and pin connection and a pin and cam slot connection between the guided member, the casing and the locking arm for giving the free end of the locking arm a swinging arc-like movement through a relatively long path measured angularly for drawing the hook-like member into tight engagement with the keeper and releasing the same from engagement with the keeper and swinging it up under and substantially parallel with the lid out of the way.

6. In a lock for a rear luggage compartment lid or other receptacle lid, the combination of a lock casing and a member guided in movement in said casing, a swinging locking arm with a hook-like end arranged to engage a keeper and a straight guide slot and pin connection and a cam slot and pin connection, with the outer end of the cam slot straight and the other end of the cam slot formed on an arc, between the guided member, the casing and the locking arm for giving the free end of the locking arm a swinging arc-like movement through a relatively 180° measured angularly and for drawing the hook-like member into tight engagement with the keeper and also for releasing the same from engagement with the keeper and swinging it up under the lid out of the way.

7. In a lock for a rear luggage compartment lid or other receptacle lid, the combination of a lock casing and a member guided in movement in said casing, a swinging locking arm with a hook-like end arranged to engage a keeper and a straight guide slot on the casing and a pin fixed on the locking arm for one connection and a pin fixed on the casing to form a pivot or a fulcrum and a cam slot on the locking arm for a second connection for giving the free end of the locking arm a swinging arc-like movement through a relatively long path measured angularly and for drawing the hook-like member into tight engagement with the keeper and also for releasing the same from engagement with the keeper and swinging it up under and nearly parallel with the lid out of the way.

8. In a lock for a rear luggage compartment lid or other receptacle lid, the combination of a lock case and a slidable member guided for reciprocating movement in the case, a swinging locking arm with a hook-like end arranged to engage a keeper and connections between the guided member, the casing and the locking arm for giving the free end of the locking arm a swinging arc-like movement through a relatively long path measured angularly for drawing the hook-like member into tight engagement with the keeper and releasing the same from engagement with the keeper and swinging it up under the lid out of the way.

RALPH H. WISE.
